(57) **CLAIM**

The ornamental design for a cigarette pack, as shown and described.

DESCRIPTION

FIG. 1 is a top front perspective view of a first embodiment of a cigarette pack of the present design.

FIG. 2 is a bottom rear perspective view of the design of FIG. 1.

FIG. 3 is a front view of the design of FIG. 1.

FIG. 4 is a rear view of the design of FIG. 1.

FIG. 5 is a right side view of the design of FIG. 1.

FIG. 6 is a left side view of the design of FIG. 1.

FIG. 7 is a top view of the design of FIG. 1.

FIG. 8 is a bottom view of the design of FIG. 1.

FIG. 9 is a top front perspective view of a second embodiment of a cigarette pack of the present design.

FIG. 10 is a bottom rear perspective view of the design of FIG. 9.

FIG. 11 is a front view of the design of FIG. 9.

FIG. 12 is a rear view of the design of FIG. 9.

FIG. 13 is a right side view of the design of FIG. 9.

FIG. 14 is a left side view of the design of FIG. 9.

FIG. 15 is a top view of the design of FIG. 9; and,

FIG. 16 is a bottom view of the design of FIG. 9.

The broken line showing of cigarettes and of crease lines in the drawings form no part of the claimed design.

1 Claim, 16 Drawing Sheets
